CONTROL SYSTEM FOR ELEVATORS

Anthony Pinto, New Rochelle, N. Y., assignor to
Otis Elevator Company, New York, N. Y., a
corporation of New Jersey

Application November 13, 1936, Serial No. 110,585

11 Claims. (Cl. 172—152)

The invention relates to control systems, and particularly to control systems for elevators.

In elevator control systems where a direct current motor is employed for raising and lowering the elevator car and is supplied with current by a variable voltage direct current generator, the generator is required to operate over a wide range of E. M. F. values, varying from a maximum in one direction to a maximum in the other. During the slow speed operation in making a stop, the generator is required to operate at low values of E. M. F. Due to the residual flux of the generator field, the E. M. F. values obtained for a given value of generator field current during the slow speed operation vary considerably, depending upon the previous magnetic state of the machine. Such variations in E. M. F. values cause undesirable variations in the operation of the car in making a stop. These variations are particularly objectionable where self-levelling apparatus is employed for bringing the car to an accurate stop regardless of whether the car over-runs or underruns the landing.

The principal object of the invention is to overcome the effects of residual flux.

The invention involves controlling the excitation of the generator during slow speed operation in such way that the generator voltage due to residual flux is reduced substantially to zero.

The invention will be described as applied to an elevator system in which self-levelling apparatus is provided to bring the car in stopping to an exact landing level.

In carrying out the invention as applied to a self-levelling elevator installation, the generator is provided with a main separately excited field winding and an auxiliary separately excited field winding, the main field winding being employed to excite the generator during operation of the car from one landing to another and the auxiliary field winding being employed to excite the generator during levelling. An auxiliary generator is provided for controlling the excitation of the main generator during levelling. The auxiliary generator is provided with a field winding which is connected in circuit with the main field winding of the main generator. The armature of the auxiliary generator is connected in the circuit with the auxiliary field winding. Upon discontinuation of the excitation of the main generator as the levelling mechanism takes control, both generators are excited by residual flux due to their previous excitation. The characteristics of the auxiliary generator are such that it acts through the main generator auxiliary field wind-

ing to provide an excitation of the main generator which reduces the residual flux of the main generator substantially to zero. Additional excitation is superimposed upon the auxiliary field winding for causing the generation of sufficient voltage to bring the car to a landing level. Due to the compensation for residual flux provided by the auxiliary generator, substantially the same generator voltage is obtained for returning the car to the landing after an overrun as for bringing it to the landing upon an underrun, thereby assuring uniform levelling operation.

A general idea of the invention, its application to a self-levelling elevator installation, and the various features and advantages thereof will be gained from the above statements. Other features and advantages of the invention will be apparent from the following description and appended claims.

The drawing is a simplified schematic wiring diagram of a portion of an elevator control system embodying the invention.

Only that part of the control system is shown from which an understanding of the invention may be readily obtained. It is to be understood that other control elements and safety elements may be added in making up the complete system and that such system is subject to many variations. It is to be further understood that the invention is applicable to various types of elevator systems such as car switch control systems, push button control systems, and other systems employing a work motor supplied with current from the generator of a motor generator set.

The electromagnetic switches have been designated as follows:

U—Up main direction switch	35
D—Down main direction switch	
LU—Up levelling direction switch	40
LD—Down levelling direction switch	
LFR—Fast speed levelling relay	
LS—Slow speed levelling switch	

Throughout the description which follows, these letters, in addition to the usual reference numerals, will be applied to the parts of the above enumerated switches. The numerals employed in designating the various elements of the wiring diagram are arranged in sequence, the lowest number appearing in the upper left hand corner 45 of the drawing, with the succeeding numbers following in numerical sequence from left to right downwardly of the sheet. The electromagnetic switches are shown in their deenergized positions.

The elevator car is designated 60 and its counterweight 55. The car is raised and lowered by means of cables passing over hoisting drum 54, which in turn is driven by elevator motor 33. 5 The elevator car is held when at rest by means of an electromechanical brake, the coil of which is designated 50. The armature of the hoisting motor is designated 41, while its field winding is designated 27. The armature of the supply generator 32 for the hoisting motor is designated 40, its main field winding 26, and its levelling field winding 37. The driving motor for the generator armature is not shown. The residual compensation generator 35 is provided with a 10 shunt field winding 34 and a main field winding 25, the main field winding being arranged in series with the main generator field winding 26. The driving motor for armature 36 of the residual compensation generator is not shown. It may be 15 driven by a motor separate from the main generator driving motor. Discharge resistances which may be provided for certain of the field windings are not shown. 11, 12, 77 and 83 designate current supply wires which may be connected to the same or different sources.

Up main direction switch U is operated to start the car in the up direction while down main direction switch D is operated to start the car in the down direction. The actuating coils 30 52 and 57 of these switches are controlled by contacts 51 and 56 respectively on the main control. These contacts may be contacts of electromagnetic switches or may be operated manually. Up direction switch U, upon operation, 35 closes contacts 15 and 24, connecting field windings 25 and 26 across supply wires 11 and 12 for current supply in a direction to cause the generation of voltage by generator 32 of a polarity to cause operation of the car in the up direction. 40 The down direction switch, upon operation, closes contacts 17 and 30, reversing the connections of the field windings to the supply wires, thereby causing the generation of voltage to operate the car in the down direction. The brake is released 45 to permit starting of the car upon operation of either direction switch, the circuit for the brake release coil 58 being established by contacts 42 upon operation of the up direction switch and by contacts 46 upon operation of the down direction 50 switch.

The car, upon being started, is accelerated by increasing the voltage of the generator and is retarded by decreasing the voltage of the generator. This control is illustrated as effected by 55 means of a resistance 20 in series with generator field winding 26, steps 21, 22 and 23 of this resistance being short-circuited in sequence by contacts 16, 14 and 13 to bring the car up to full speed and being reinserted in reverse sequence to 60 slow the car down to a slow speed preparatory to stopping.

The levelling mechanism acts to bring the car to an exact landing level in case it underruns or overruns the landing at which a stop is being made. The levelling mechanism is rendered ineffective in starting the car and is rendered effective during the slow down operation. The levelling electromagnetic switches are controlled by contacts 66, 71, 73 and 75 of the levelling control. These contacts may be operated mechanically, as by the cooperation of cams with rollers on operating arms for the contacts, by relative movement of the cams and rollers, or inductively, as by the magnetic cooperation of electromagnetic switch structure with magnetizable plates,

by relative movement of the structure and the plates, or in any other suitable way. Contacts 66 and 75 are fast speed levelling contacts while contacts 71 and 73 are slow speed levelling contacts. These contacts act through the levelling electromagnetic switches to provide two speed levelling. A two speed levelling zone is provided on each side of each landing. Contacts 66 and 71 engage as the car enters the up fast speed levelling zone for the landing at which a stop is being made. As the car enters the up slow speed levelling zone, contacts 66 separate. Contacts 71 separate just before the car reaches the exact floor level. Similarly, contacts 75 and 73 engage as the car enters the down fast speed 15 levelling zone for the landing at which a stop is being made. As the car enters the down slow speed levelling zone, contacts 75 separate. Contacts 73 separate just before the car reaches the exact floor level. 20

Assume that the car has been running in the up direction, that slow down has been initiated preparatory to bringing the car to a stop at a landing, and that the levelling mechanism has been rendered effective. Upon arrival of the car 25 in the up fast speed levelling zone for the landing, up levelling switch contacts 66 and 71 are engaged. The engagement of contacts 66 completes a circuit for coil 67 of fast speed levelling relay LFR. This relay operates to open its contacts 30 68 to prevent the energization of coil 65 of slow speed levelling switch LS. The engagement of contacts 71 completes the circuit for coil 72 of up levelling direction switch LU. This switch closes contacts 76 and 85 to prepare the 35 circuit for levelling field winding 37 for current supply thereto in a direction to excite the generator for continued upward movement of the car. The up main direction switch is maintained operated during slow down preferably 40 until the car enters the fast speed levelling zone. Upon dropping out, the up main direction switch opens contacts 15 and 24 to deenergize generator main field winding 26. At the same time, however, it closes contacts 80 to complete the circuit 45 for generator levelling field winding 37. Thus the generator excitation for the levelling operation is provided by field winding 37, the excitation being such as to cause the car to run at a fast levelling speed. The brake is maintained 50 released by contacts 47 of up levelling direction switch LU, which maintain the brake release coil energized after the opening of contacts 42 of up main direction switch U.

The elevator car continues to run at a fast 55 levelling speed until it enters the slow speed levelling zone. As this point is reached, contacts 66 separate to deenergize coil 67 of the fast speed levelling relay. This relay, upon dropping out, closes contacts 63, which completes, through up 60 main direction switch contacts 61, now closed, and up levelling direction switch contacts 64, a circuit for coil 65 of slow speed levelling switch LS. This switch operates to open contacts 45, inserting resistance 46 in the circuit for generator levelling field winding 37. This reduces the excitation of the generator provided by field winding 37, causing the car to run at a slow levelling speed.

Just before the car reaches an exact level with 70 the landing, contacts 71 separate to deenergize coil 72 of the up levelling direction switch. This switch drops out, opening contacts 76 and 85 to deenergize levelling field winding 37. It also opens contacts 47 to deenergize brake release coil 75

50. Thus, the brake is applied, bringing the car to rest level with the landing.

Similar operation is effected in bringing the car to a stop at a landing during downward car travel. Upon the arrival of the car in the down fast speed levelling zone for the landing, down levelling switch contacts 75 and 73 are engaged. The engagement of contacts 75 causes the operation of fast speed levelling relay LFR to prevent the operation of slow speed levelling switch LS. The engagement of contacts 73 completes the circuit for coil 74 of down levelling direction switch LD. This switch closes contacts 82 and 84 to prepare the circuit for levelling field winding 37 for current supply thereto in a direction to excite the generator for continued downward movement of the car. As in the case of the up main direction switch, the down main direction switch is maintained operated during slow down preferably until the car enters the fast speed levelling zone. Upon dropping out, the down main direction switch opens contacts 77 and 30 to deenergize generator main field winding 26 and at the same time closes contacts 81 to complete the circuit for generator levelling field winding 37. Thus excitation for the generator is provided by field winding 37 for the levelling operation to cause the car to run at a fast levelling speed. The brake is maintained released during levelling by contacts 53 of down levelling direction switch LD.

As the car enters the slow speed levelling zone, contacts 75 separate to cause the deenergization of fast speed levelling relay LFR and thus the operation of slow speed levelling switch LS. This switch operates to insert resistance 46 in the circuit for field winding 37, reducing the generator excitation sufficiently to cause the car to run at a slow levelling speed. Just before the exact landing level is reached, contacts 73 separate, causing the dropping out of the down levelling direction switch LD. This switch opens contacts 82 and 84 to deenergize levelling field winding 37, and also opens contacts 53 to deenergize brake release coil 50. Thus the brake is applied, bringing the car to rest level with the landing.

In the event that the car, in making a stop at a landing, overruns the floor, the levelling mechanism acts to cause the car to be returned to the landing level. Assume, for example, that the car has been travelling in the up direction and, in making a stop at a landing, overruns the floor. If the overrun extends into the down fast speed levelling zone, both contacts 75 and 73 engage, causing the operation of down levelling direction switch LD and fast speed levelling relay LFR. Down levelling direction switch LD, by engaging contacts 53, 82 and 84, causes the release of the brake and the application of voltage to levelling field winding 37 of a polarity to cause the car to be returned to the landing. As the down slow speed levelling zone is reached, contacts 75 separate to cause the insertion of resistance 46 in circuit with field winding 37 to reduce the speed of the car. Just before the landing level is reached, contacts 73 separate to deenergize the down levelling direction switch, resulting in the deenergization of field winding 37 and the application of the brake to bring the car to a stop. Should the overrun extend only into the slow speed levelling zone, relay LFR is not operated, so that slow speed levelling switch LS is operated immediately upon operation of the levelling direction switch. Thus resistance 46 is inserted

in circuit with field winding 37, causing the car to be returned to the floor at slow levelling speed.

The armature 36 of residual compensation generator 35 is in series with generator levelling field winding 37. This generator acts during levelling to compensate for the effects of residual flux of the generator field. Due to the relatively low value of generator excitation for levelling, the residual flux of the generator field forms a large percentage of the total flux and therefore affects the operation of the system very markedly. Unless its effect is overcome, it causes the value of the excitation voltage generated, when the external exciting current is of the same value for returning the car to a floor after an overrun as for causing it to continue to the floor during an underrun, to be much less for returning the car to the floor than for causing it to continue to the floor during the underrun. Furthermore, the value of these voltages may vary, depending upon the previous magnetic state of the machine, which in turn determines the shape of the hysteresis loop and thus the amount of residual flux. Such differences in voltage are undesirable under levelling conditions. If the effects of residual flux are overcome, the system may be adjusted so as to obtain more uniform levelling results. This is done in the system illustrated by compensating for the effects of residual flux by means of residual compensation generator 35.

The residual compensation generator may be started in operation during slow down so that it is running at full speed at the time that the excitation of the main generator is transferred from its main field winding 26 to its levelling field winding 37, or it may be driven all the time the main motor generator set is in operation. As field winding 25 of the residual compensation generator and field winding 26 of the main generator are connected in series, they are subject to the same current variations. At the instant field winding 26 is disconnected, there is a voltage generated by the main generator due to the residual flux of the generator field. There is also a voltage generated by the residual compensation generator due to the residual flux of its field. Since the same exciting current has been supplied to both field windings 25 and 26, the value of the residual voltage of the residual compensation generator is substantially proportional to that of the residual voltage of the main generator. The residual compensation generator is designed so that if, upon disconnection of field windings 25 and 26 from the source, armature 36 is connected directly across field winding 37 in such way as to produce a magnetizing force which opposes the residual flux of the main generator, the voltage of the main generator would be reduced to zero.

Thus, with the armature of the residual compensation generator connected in series with field winding 37, the residual voltage of the main generator is eliminated so that the application of an external voltage to field winding 37 produces substantially the same value of fast speed levelling voltage for returning the car to the landing after an overrun as for bringing it to the floor during an underrun.

The insertion of resistance 46 in the circuit for field winding 37 for slow speed levelling, unless counteracted, reduces the voltage applied to this field winding by the residual compensation generator due to the voltage drop across this resistance. To maintain the residual compensation voltage at proper value to overcome the effects of residual flux at the time resistance 46 is inserted

is inserted, slow speed levelling switch LS, in removing the shunt circuit for resistance 46, closes contacts 43 to connect shunt field winding 34 across armature 36 of the compensation generator. This shunt field winding is wound so that the self-excitation of the generator produced thereby counteracts the voltage drop across resistance 46 to such extent as to maintain the voltage of the compensation generator of proper value to compensate for residual flux of the main generator. The direction of the excitation of shunt field winding 34, being dependent upon the residual flux of the residual compensation generator 35 produced by field winding 25, is always correct.

It is to be understood that, in order to minimize circulating current in the motor armature-generator armature loop circuit when the car is stopped, main field winding 26 may be connected across armature 40 of the main generator in such way as to counteract the residual flux of the generator field. Such arrangement is termed a "suicide" connection. Instead of this arrangement, when the car is stopped armature 36 may be connected directly across field winding 37, this field winding being disconnected from supply mains 77 and 83 and slow speed levelling switch LS being dropped out when the car is stopped. In such case, the effects of residual flux are overcome and the circulating current is reduced substantially to zero while the car is at rest, it being understood that the residual compensation generator is maintained in operation while the car is standing.

35 In case of polyphase alternating current supply to the building in which the elevator is installed, power supply for wires 11 and 12 may be obtained from an exciter which may be driven by the driving motor of the motor generator set or by a 40 separate driving motor. Wires 77 and 83 also may be supplied from this exciter. On the other hand, wires 77 and 83 may be supplied with current from a separate exciter, regardless of the 45 type of power supply to the building or the manner in which current is supplied to wires 11 and 12. With such arrangement, a reduction in voltage for slow speed levelling may be obtained by reducing the excitation of this separate exciter and the shunt field winding of the residual compensation generator may be omitted.

50 It is to be understood that an arrangement may be provided for compensating for variations in load on the elevator hoisting motor, particularly during levelling. Where wires 77 and 83 are supplied from a separate exciter, load compensation during levelling may be obtained by providing this exciter with a separately excited load compensating field winding connected across resistance in the loop circuit of the armature 55 of the elevator hoisting motor and the armature of the main generator. With the control of the generator voltage for fast and slow speed levelling effected by controlling the excitation of the separate exciter, proper load compensation is provided by this load compensating field winding for both levelling speeds. However, with resistance 46 arranged in the circuit for field winding 37, it may be desirable, upon the insertion of this 60 resistance by operation of switch LS, for switch LS to increase the effect of the load compensating field winding of the separate exciter to insure proper load compensation. Load compensation for levelling may also be effected by a series field winding on the main generator, rendered effective only for the levelling operation. In case it is

desired to use this series field winding for load compensation for fast speed operation as well, another field winding may be connected in the loop circuit of the armature of the elevator hoisting motor and main generator and arranged on 5 the residual compensation generator to insure the proper residual flux compensation.

Although a two speed levelling system has been described, it is to be understood that the invention is applicable to single speed levelling systems. Also, the invention is applicable to one way levelling systems in which the car is operated at slow speed prior to stopping but is not automatically returned to the landing after an overrun.

Many elevator control systems are very complex and admit of many variations. In applying the invention to such control systems, variations in the manner in which the excitation of the generator is controlled may be made with the 20 view of adapting the invention more readily to such control systems. These and other changes in the manner of controlling the generator excitation may be made which do not depart from the spirit and scope of the invention. It is therefore intended that all matter contained in the above description or shown in the accompanying drawing shall be interpreted as illustrative and not in a limiting sense.

What is claimed is:

1. In combination; an elevator car; a direct current hoisting motor therefor; a variable voltage generator for supplying current to said motor; means for variably exciting said generator in the operation of said car from one landing to another; and means for causing said car to operate at slow speed prior to stopping at a landing, said last named means comprising means for exciting said generator in a direction to oppose the residual flux of the generator and in an amount, 40 determined by the excitation of said generator during operation of the car to such landing, to compensate for the residual flux and in addition in a direction and amount for causing the generation of voltage for operating the car at said 45 slow speed.

2. In combination; an elevator car; a direct current hoisting motor therefor; a variable voltage direct current generator for supplying current to said motor; means for exciting said generator to effect movement of said car from one landing to another; and means for exciting said generator to cause the car to operate at a slow speed to bring it to a level with the landing at which a stop is being made, said last named 55 means comprising means for causing the excitation of said generator for such slow speed to be controlled in accordance with the excitation of said generator during said movement of said car to the landing at which the stop is being made 60 to compensate for the residual flux of the generator.

3. In combination; an elevator car; a direct current hoisting motor therefor; a main direct current generator for supplying current to said 65 motor; means for causing excitation of said main generator to effect movement of said car from one landing to another; and means for causing excitation of said main generator to level the car with the landing at which a stop is being 70 made, regardless of whether the car overruns or underruns the landing, said last named means comprising an auxiliary direct current generator for exciting said main generator in a direction to oppose the residual flux of said main generator, 75

and means for exciting said auxiliary generator in proportion to the residual flux of said main generator and to such extent as to reduce the voltage of the main generator due to residual flux substantially to zero.

4. In combination; an elevator car; a direct current hoisting motor therefor; a main direct current generator for supplying current to said motor; means for causing excitation of said main generator to effect movement of said car from one landing to another; and means for causing excitation of said main generator to level the car with the landing at which a stop is being made, regardless of whether the car overruns or under-
10 runs the landing, said last named means comprising an auxiliary direct current generator, means for exciting said auxiliary generator by residual flux proportional to the residual flux of said main generator and means for causing said auxiliary generator to excite said main generator in such way and to such extent as to reduce the voltage thereof due to residual flux substantially to zero.

5. In combination; an elevator car; a direct current hoisting motor therefor; a main direct current generator for supplying current to said motor; means for causing excitation of said main generator to effect movement of said car from one landing to another; means for causing excitation of said main generator to level the car with the landing at which a stop is being made, regardless of whether the car overruns or underruns the landing; and means for overcoming the effects of residual flux of said main generator during levelling, said last named means comprising an auxiliary direct current generator for controlling the excitation of said main generator during levelling and means for exciting said auxiliary generator in accordance with the previous excitation of said main generator.

6. In combination; an elevator car; a direct current hoisting motor therefor; a main direct current generator for supplying current to said motor, said generator having a main field winding and an auxiliary field winding; means for causing excitation of said main generator by said main field winding to effect movement of said car from one landing to another; and means for causing excitation of said main generator by said auxiliary field winding to level the car with the landing at which a stop is being made, regardless of whether the car overruns or underruns the landing, said last named means comprising an auxiliary direct current generator for exciting said auxiliary field winding in a direction to oppose the residual flux of said main generator, and means for exciting said auxiliary generator in proportion to the residual flux of said main generator and to such extent as to effect a reduction of the voltage of the main generator due to residual flux substantially to zero.

7. In combination; an elevator car; a direct current hoisting motor therefor; a main direct current generator for supplying current to said motor, said generator having a main separately excited field winding and an auxiliary separately excited field winding; means for causing excitation of said main generator by said main field winding to effect movement of said car from one landing to another; means for causing excitation of said main generator by said auxiliary field winding to level the car with the landing at which a stop is being made, regardless of whether the car overruns or underruns the landing; and means for overcoming the effects of residual flux of said main generator during levelling, said last

named means comprising an auxiliary direct current generator for controlling the excitation of said auxiliary field winding and means for exciting said auxiliary generator in accordance with the previous excitation of said main generator.

8. In combination; an elevator car; a direct current hoisting motor therefor; a main direct current generator for supplying current to said motor, said generator having a main field winding and an auxiliary field winding; means for causing excitation of said main generator by said main field winding to effect movement of said car from one landing to another; and means for discontinuing excitation of said main generator by said main field winding and for causing its excitation by said auxiliary field winding to level the car with the landing at which a stop is being made, regardless of whether the car overruns or underruns the landing, said last named means comprising an auxiliary direct current generator for exciting said auxiliary field winding in a direction to oppose the residual flux of said main generator, said auxiliary generator having its armature connected in series with said auxiliary field winding and its field winding connected for excitation in accordance with the excitation of said main field winding so as to excite said auxiliary generator during levelling by residual flux to such extent as to provide excitation of the main generator which overcomes the residual flux of the main generator.

9. In combination; an elevator car; a direct current hoisting motor therefor; a direct current generator for supplying current to said motor, said generator having a main separately excited field winding and an auxiliary separately excited field winding; means for causing excitation of said generator by said main field winding to effect movement of said car from one landing to another; means for causing excitation of said generator by said auxiliary field winding to level the car with the landing at which a stop is being made, regardless of whether the car overruns or underruns the landing; and means for overcoming the effects of residual flux of said generator during levelling, said last named means comprising a direct current generator having an armature connected in series with said auxiliary field winding and a separately excited field winding connected in circuit with said main field winding.

10. In combination; an elevator car; a direct current hoisting motor therefor; a direct current generator for supplying current to said motor, said generator having a main separately excited field winding and an auxiliary separately excited field winding; means for causing excitation of said generator by said main field winding to effect movement of said car from one landing to another; means for discontinuing excitation of said generator by said main field winding and for causing its excitation by said auxiliary field winding to level the car with the landing at which a stop is being made, regardless of whether the car overruns or underruns the landing; and means for overcoming the effects of residual flux of said generator during levelling, due to the previous excitation provided by said main field winding, said last named means comprising a direct current generator having an armature connected in series with said auxiliary field winding and a separately excited field winding connected in series with said main field winding.

11. In combination; an elevator car; a direct current hoisting motor therefor; a direct current generator for supplying current to said motor,

said generator having a main separately excited field winding and an auxiliary separately excited field winding; means for connecting said main field winding to a source of direct current to effect movement of said car from one landing to another; means for disconnecting said main field winding and for connecting said auxiliary field winding to a source of direct current to level the car with the landing at which a stop is being made regardless of whether the car overruns or under-runs the landing; means for causing the car to operate at two different levelling speeds, dependent upon the distance of the car from said landing during the levelling operation, said means comprising resistance in series with said auxiliary

field winding and means for short-circuiting said resistance to effect a fast levelling speed and for removing said short-circuit to effect a slow levelling speed; and means for overcoming the effects of residual flux of said generator during levelling, said last named means comprising an auxiliary direct current generator having an armature connected in series with said auxiliary field winding, a separately excited field winding connected in series with said main field winding, an additional field winding, and means for connecting said additional field winding across the armature of said auxiliary generator while said short-circuit for said resistance is removed.

ANTHONY PINTO.
